US00D729432S

(12) **United States Design Patent**
Newton et al.

(10) **Patent No.:** US D729,432 S
(45) **Date of Patent:** ** May 12, 2015

(54) **LUMINAIRE**

(71) Applicants: **Chad Stuart Newton**, Tyrone, GA (US);
Christopher Michael Bryant, Social Circle, GA (US)

(72) Inventors: **Chad Stuart Newton**, Tyrone, GA (US);
Christopher Michael Bryant, Social Circle, GA (US)

(73) Assignee: **Cooper Technologies Company**, Houston, TX (US)

(**) Term: **14 Years**

(21) Appl. No.: **29/475,915**

(22) Filed: **Dec. 9, 2013**

(51) LOC (10) Cl. **26-03**

(52) U.S. Cl. **D26/92**

(57) **CLAIM**

The ornamental design for a luminaire, as shown and described.

DESCRIPTION

FIG. 1 is a front perspective view of a luminaire, showing our new design;

FIG. 2 is a rear perspective view thereof;

FIG. 3 is a top plan view thereof;

FIG. 4 is a bottom plan view thereof;

FIG. 5 is a left-side elevational view thereof;

FIG. 6 is a right-side elevational view thereof;

FIG. 7 is a front elevational view thereof; and

FIG. 8 is a rear elevational view thereof.

FIG. 9 is a front perspective view of another embodiment of the luminaire, showing our new design;

FIG. 10 is a rear perspective view thereof;

FIG. 11 is a top plan view thereof;

FIG. 12 is a bottom plan view thereof;

FIG. 13 is a left-side elevational view thereof;

FIG. 14 is a right-side elevational view thereof;

FIG. 15 is a front elevational view thereof; and

FIG. 16 is a rear elevational view thereof.

FIG. 17 is a front perspective view of yet another embodiment of the luminaire, showing our new design;

FIG. 18 is a rear perspective view thereof;

FIG. 19 is a top plan view thereof;

FIG. 20 is a bottom plan view thereof;

FIG. 21 is a left-side elevational view thereof;

FIG. 22 is a right-side elevational view thereof;

FIG. 23 is a front elevational view thereof; and,

FIG. 24 is a rear elevational view thereof.

The broken lines in the figures represent unclaimed subject matter and form no part of the claimed design.

1 Claim, 20 Drawing Sheets
